UNITED STATES PATENT OFFICE.

JOHN DARNLEY TAYLOR, OF LONDON, ENGLAND.

APPARATUS FOR IMPREGNATING OR TREATING TEXTILE FABRICS AND OTHER MATERIALS.

Specification of Letters Patent. Patented Feb. 24, 1920.

1,331,729.

Application filed November 14, 1917. Serial No. 201,991.

To all whom it may concern:

Be it known that I, JOHN DARNLEY TAYLOR, a subject of the King of Great Britain, residing at London, England, have invented 5 new and useful Improvements in and Relating to Apparatus for Impregnating or Treating Textile Fabrics and other Materials, of which the following is a specification.

10 This invention has reference to apparatus for impregnating or treating textile fabrics and other materials with solutions or compositions containing volatile constituents and it is the object of the invention to provide 15 an improved apparatus for this purpose adapted not only to effect a thorough impregnation of the material under treatment with the desired solution or composition but also to effect the recovery of the volatile constituents of the solution thereby effecting 20 considerable economy.

With this object in view and such others as may hereinafter appear or are incidental thereto the invention may be said to be embodied in a construction for the purpose set forth comprising an impregnating chamber and a drying chamber means for maintaining a vacuum in said chambers, means co-operating with said chambers for drying the 25 material under treatment and impregnating it with a solution containing volatile constituents, means for drying said material after impregnation and means for recovering the volatile constituents of said solution.

30 In order that my invention may be readily understood and carried into effect I will proceed to describe the same fully for which purpose reference is to be had to the accompanying drawing which:—

35 Illustrates diagrammatically a longitudinal section of an apparatus constructed in accordance with this invention parts being shown in elevation.

In that embodiment of the invention illustrated the numeral 1 indicates an impregnating chamber and 2 a drying chamber communicating therewith. Rotatably mounted in the chamber 1 in ball or other antifriction bearings are spindles 3 and 4 serving for 40 the reception of the fabric or the like to be treated while a tank 5 is also provided within said chamber 1 for the solution or composition with which said fabric is to be impregnated. The tank 5 is in communica-

tion with a storage reservoir 6 by means 55 of the pipe connection 7 in which suitable valves 8 and 9 are arranged and within the tank near the bottom thereof a suitable guide roll 10 is mounted in antifriction bearings while scraper blades 11 are also arranged 60 within said tank to remove the superfluous solution from the fabric as it passes between them as will be presently explained. A guide roll 12 and guiding and squeezing rolls 13, 14 and 15 are rotatably mounted in 65 antifriction bearings within the chamber 1 said rolls serving to guide and squeeze the impregnated fabric on its passage to and from the drying chamber 2 the construction of which I will now proceed to describe. It 70 comprises a rectangular box-like structure having a plurality of preferably steam heated chests or drying shelves 16 through which steam may be circulated in any well known manner and provided with suitable 75 guide rolls 17 mounted to rotate in antifriction bearings. Appropriate doors 18 and inspection windows 19 are provided in the side walls of the chamber 2 and a door 20 is arranged at the end for cleaning or other 80 purposes. Near the end of the chamber 2 an outlet 21 is provided for the volatile constituents of the impregnating solution said outlet being of elongated formation extending approximately from side to side of the drying chamber 2 and connected to a condenser 22 preferably of the multitubular type which in turn is connected to a receiving tank 23 divided by a horizontal partition into two 85 compartments 24 and 25 communicating 90 with each other by a pipe 26 having a valve 27 therein. The compartment 24 of the receiver 23 is connected to a vacuum pump 28 actuated by an appropriate engine 29.

The operation of the apparatus above described is as follows: Steam having been admitted to the steam heated chests or plates 16 to heat up the chamber 2 a roll 30 of canvas, paper or other desired material is mounted upon the spindle 3 in the chamber 100 1 and the free end of said material clamped or otherwise suitably secured to the end of a leader belt 32 already in position within the apparatus. The door 31 of the chamber 1 is closed, the vacuum pump 28 set in operation and the spindles 3 and 4 driven from a suitable source of power—which may be the engine 29—by gearing which however 105

is not shown as it may be of any appropriate construction. By the time the end of the leader belt 32 to which the material is joined approaches the rolls 13—15—which can be ascertained from a suitable inspection window 32' in the chamber 1—the pump 28 will have exhausted the atmospheric contents of the chambers 1 and 2 and that portion of the fabric under treatment which has passed between the steam heated chests 16 will have been thoroughly dried and the air in the interstices thereof extracted.

The valves 8 and 9 in the pipe connection 7 are then opened and the impregnating solution in the storage vessel 6 will flow into the tank 5 under the influence of the vacuum obtaining within the chambers 1 and 2. As the fabric passes under the roller 10 it becomes impregnated with the solution which owing to the vacuum sinks into the fabric and is pressed into all the minute interstices or pores thereof as it winds onto the spindle 4. When the whole of the material is wound upon the spindle 4 the direction of rotation of spindles 3 and 4 is reversed and the material again passes through the tank 5 and the superfluous solution removed by the scraper blades 11. It then passes between the rolls 15, 14 and 13 and between the heated chests or plates 16 and the volatile constituents of the solution with which it is impregnated are thus driven off and drawn through the elongated aperture 21 into the condenser 22 from which said constituents are delivered in liquid form to the receiver 23 from the lower compartment 25 of which they may be abstracted as required without destroying the vacuum in the chambers 1 and 2 by closing the valve 27 and opening the vacuum break cock 27' in the compartment 25. The material when completely wound upon the spindle 3 is in a dry condition and may be then removed from the apparatus.

It will be seen that under my invention I have provided an apparatus for rapidly and efficiently impregnating textile or other material with solutions containing volatile constituents and for recovering said volatile constituents for further use in which the risk of danger arising from the formation of an explosive mixture of air and inflammable vapors is reduced to a minimum for it is to be noted that the whole of the operation is conducted in the absence of atmospheric air while as a further safeguard against accident arising from friction of the moving parts all rolls and spindles are mounted in anti-friction bearings.

What I claim and desire to secure by Letters Patent is:—

1. In impregnating textile fabrics and other materials with solutions containing volatile constituents, conducting the material through a heated vacuum chamber

adapted to exhaust moisture and air therefrom, then passing the material through an impregnating solution and winding the same upon a receiving roll disposed in said impregnating chamber and above the said solution and after impregnation conducting the material back through the impregnating solution and the heated vacuum chamber on to the delivery roll so as to dry the impregnated material and extract the volatile constituents of the impregnating solution.

2. In impregnating textile fabrics and other materials with solutions containing volatile constituents, conducting the material through a heated vacuum chamber adapted to exhaust moisture and air therefrom, then passing the material through the impregnating solution in the vacuum chamber and winding same upon a receiving drum disposed in said impregnating chamber above the said solution and after impregnation conducting the material back through the impregnating solution and the heated vacuum chamber on to the delivery roll to dry the same and extract and withdraw the volatile constituents of the impregnating solution during the continuance of the process of impregnation.

3. In vacuum apparatus for impregnating or treating textile fabrics and other materials with solutions or composition containing volatile constituents, the combination with the impregnating chamber, of a drying chamber in open communication therewith, delivery and winding rolls mounted in said impregnating chamber, a tank situated in the impregnating chamber for the impregnating solution, means for conducting the fabric through the tank, means for extracting air and moisture and the volatile constituents and condensing the last and maintaining a vacuum in the said chambers, and means whereby the portions of the condensate can be withdrawn from the system during the working thereof without lowering the vacuum.

4. In vacuum apparatus for impregnating or treating textile fabrics and other materials with solutions or compositions containing volatile constituents, the combination with the impregnating chamber, of a drying chamber in open communication therewith, delivery and winding rolls mounted in said impregnating chamber, a tank for impregnating solution in said impregnating chamber, means for conducting the fabric through the tank, means for heating the drying chamber, means for extracting air from said drying and impregnating chambers and from the material undergoing treatment, means for reversing the movement of the conducting means, means for extracting the volatile constituents and condensing the last and maintaining a vacuum in the said chambers, and means whereby the

portions of the condensate can be withdrawn from the system during the working thereof without lowering the vacuum.

5. In vacuum apparatus for impregnating or treating textile fabrics and other materials with solutions or compositions containing volatile constituents, the combination with an impregnating chamber, a tank in said chamber for the impregnating solution and rolls in said chamber for guiding the fabric through the impregnating solution in said tank, of a storage vessel in communication with said tank, a drying chamber in communication with said impregnating chamber, means for maintaining a vacuum in the chambers, means for regulating the feeding of the aforesaid tank with impregnating solution, means for extracting the volatile constituents and condensing the last and maintaining a vacuum in the said chambers, and means whereby the portions of the condensate can be withdrawn from the system during the working thereof without lowering the vacuum.

25. 6. In vacuum apparatus for impregnating or treating textile fabrics and other materials with solutions or compositions containing volatile constituents, the combination with an impregnating chamber, of a tank for holding impregnating solution in said chamber, a drying chamber in open communication with and forming an extension of said impregnating chamber, means in the impregnating chamber for receiving and guiding the material through the impregnating solution, means for conducting the fabric through the drying chamber, means for re-

versing the movement of the guiding and conducting means, means for maintaining a vacuum in the drying and impregnating 40 chambers and thereby extracting the volatile constituents and condensing the last and maintaining a vacuum in the said chambers, and means whereby the portions of the condensate can be withdrawn from the system 45 during the working thereof without lowering the vacuum.

7. In vacuum apparatus for impregnating or treating textile fabrics and other materials with solutions or compositions containing volatile constituents, the combination with an impregnating chamber, of a drying chamber constituted by an extension of said impregnating chamber in open communication therewith, antifriction rolls in 50 the impregnating chamber for receiving and guiding the material through the impregnating solution, a leader belt for conducting the leading end of the material, steam containers in the drying chamber, antifriction supporting and guiding rolls in said drying chamber and situated relatively to said steam containers, means for rotatively operating the rolls in the impregnating chamber in either direction so as to cause the material to 55 travel forward and backward in the said impregnating and drying chambers, means for withdrawing the volatile constituents and condensing the last and maintaining a vacuum in the said chambers, and means whereby 60 the portions of the condensate can be withdrawn from the system during the working thereof without lowering the vacuum.

JOHN DARNLEY TAYLOR.
